ABSTRACT OF THE DISCLOSURE

A magnetostrictive vibratory element or lamination composed of a thin flat rectangular coupling member of non-magnetic material, such as aluminum, to opposite faces of which are bonded relatively thin and short rectangular sheets or layers of magnetostrictive material, such as nickel, which extends across the width of such faces at their midlength, and an array of such laminations abutting one another with their aluminum strips bonded at one end to a face of a radiating plate and an energizing coil electromagnetically coupled to their nickel-clad regions.

BACKGROUND OF THE INVENTION

Field of the invention

Magnetostrictive transducer apparatus for ultrasonic agitation of a liquid.

Description of the prior art

Ultrasonic transducer apparatus in which thin U-shaped corrugation-containing laminations of magnetostrictive material are arranged with distributed spacing between laminations and are bonded at their one end to a radiating plate, as disclosed in U.S. Patents 3,161,792 and 3,173,037, are being employed with considerable success. The material and fabricating of such laminations and their mounting on the radiating plate tends to be somewhat costly.

SUMMARY

According to the present invention, the non-magnetic members couple the magnetostrictive material thereon to the plate at spacing intervals determined by the thickness of such members, which may be varied to suit requirements. Fabrication of the novel vibratory elements and of the transducer assemblage is relatively simple.

BRIEF DESCRIPTION OF THE DRAWING

FIGS. 1 and 2 are front and side elevation views of a magnetostrictive vibratory element constructed in accord with the present invention; and

FIGS. 3 and 4 are front and side elevation views of a novel transducer assemblage embodying vibratory elements constructed in accord with that shown in FIGS. 1 and 2.

DESCRIPTION OF THE PREFERRED EMBODIMENT

Referring to the drawings, the exemplified vibratory elements 5 of the present invention comprises a thin flat coupling member 6 of relatively inexpensive non-magnetic material such as aluminum to opposite faces of which are bonded, as by epoxy cement, respective thin sheets 7 of magnetostrictive material, such as nickel, which extend the full width of such member and cover a portion one-half for example, of the length or height of such member in a mid-length region for maximum vibratory effectiveness. The member 6 is preferably one-

2

half wavelength long at the operating frequency, and the magnetostrictive sheets 7 are preferably one-quarter wavelength long. The aluminum member 6 may be such as one-eighth inch thick which determines the spacing between abutting magnetostrictive sheets 7 on adjacent vibratory elements 5.

Referring to FIGS. 3 and 4, the novel vibratory elements 5 will be dimensioned to extend substantially the full width of the radiating plate 8 to which they are bonded at their one end, their output end, as by epoxy cement. The elements are arranged in groups 9, of six or so, for example, with the elements 5 of each group abutting one another at their magnetostrictive sheets 7. To change the spacing of the abutting pairs of magnetostrictive sheets, the thickness of the aluminum member 6 would be made to suit.

For energizing the magnetostrictive sheets to vibrate the members 6 in a longitudinal mode, hence drive the coupling plate 8 uniformly across its face, each alternate group 9 of vibratory elements 5 is provided with a pre-formed coil 10 which encircles such group in the region of such magnetostrictive sheets. The adjacent groups not provided with their own coils are also driven by the nearby coils 10 via electromagnetic coupling therewith.

The radiating plate 8 may constitute the bottom of a cleaning tank 11 as shown for ultrasonic agitation of a liquid medium within such tank, or such plate may form the working wall of an immersible transducer (not shown) for disposition within a separate tank.

I claim as my invention:

1. A magnetostrictive vibratory element (5) comprising:
a thin coupling member (6) of non-magnetic material for transmission of vibrational energy along its length to an output end; and
layers (7) of magnetostrictive material of less length than said coupling member secured to its opposite faces and disposed away from its output end.

2. The vibratory element of claim 1, wherein said coupling member (6) is of a thin, flat, rectangular form and said layers (7) are of flat thin-sheet magnetostrictive material bonded to said member at a mid-length region thereof.

3. The vibratory element of claim 1, wherein said layers (7) of magnetostrictive material extend substantially the full width of said coupling member (6) at a mid-length region thereof and are of a length substantially one-half that of said member.

4. The vibratory element of claim 2, wherein said coupling member (6) is of aluminum and said layers of thin-sheet magnetostrictive material are no greater than five mils thick.

5. A transducer assemblage comprising,
a thin flat radiating plate (8);
a plurality of flat parallel-arranged abutting vibratory elements (5) bonded at their one edge to a face of said radiating plate,
said vibratory elements each comprising a flat coupling member (6) of non-magnetic material having layers (7) of magnetostrictive material secured to opposite faces thereof at a mid-length region; and
preformed energizing coil means (10) electromagnetically coupled to said magnetostrictive layers (7).

6. The transducer assemblage of claim 5, wherein the vibratory elements (5) are substantially the width of said radiating plate (8) and are arranged in groups (9) in their thickness direction, and said coil means (10) comprises a number of coils encircling every other one of such groups.

7. A transducer assemblage comprising,
a radiating plate,

a plurality of coupling members of non-magnetostrictive material bonded at their one edge to said radiating plate,
 thin layers of magnetostrictive material bonded to surface regions of said coupling members and spaced away from their plate-bonded ends, and energizing coil means electromagnetically coupled to said layers of magnetostrictive material.
